UNITED STATES PATENT OFFICE.

THOMAS J. GARRIGAN, OF BOSTON, MASSACHUSETTS.

CANDLE.

SPECIFICATION forming part of Letters Patent No. 701,557, dated June 3, 1902.

Application filed April 19, 1902. Serial No. 103,685. (No model.)

To all whom it may concern:

Be it known that I, THOMAS J. GARRIGAN, a citizen of the United States, and a resident of Boston, county of Suffolk, State of Massachusetts, have invented an Improvement in Candles, of which the following description, in connection with the accompanying drawings, is a specification, like letters on the drawings representing like parts.

10 The invention to be hereinafter described relates to candles wherein a wick extending throughout the length of the candle is employed. Should the wick continue to burn the full length of the candle, the material of 15 the wick would flow and fill or cover whatever holder might be supporting the candle.

In connection with church-service and other places where candle sticks or holders are frequently of silver or other valuable material 20 and often highly ornamental it is a great desideratum that the candle does not burn completely down to the holder which embraces the butt. It is desirable that the candle shall be self-extinguishable before the wick is wholly 25 consumed and that at the extinguishing-point the capillarity of the wick by which the oils and vapors of combustion are carried to the flame shall be destroyed and the flame be effectually extinguished, so that all smoldering 30 and smoking of the wick may be avoided, and these results I have secured by treating a portion of the lower end of the wick which extends continuously throughout the length of the candle with a composition which will 35 harden upon the material of the wick as the flame reaches it, and thus effectually destroy the capillarity of the wick and extinguish the flame.

Referring to the drawing forming part of 40 this case, A represents a candle composed of any usual or suitable material, and B its wick.

Let C represent a part of any suitable holder which receives the butt-end of the candle.

45 To prevent the wick from burning to the line x, which may represent the upper end of the holder, I have provided the wick for a short distance above said line with a non-burnable section, so that as soon as the fire 50 in the wick arrives at the non-burnable section the candle is self-extinguished.

I may practice my invention in several different ways. I may apply to the fibrous material of the wick a material which will not burn—as, 55 for instance, I may treat the portion of the

wick represented by the stipple portion a with a non-inflammable compound that will preferably harden when heated, so that as the heat from the wick reaches the treated portion a thereof the compound is hardened sufficiently to effectually extinguish the light and destroy to a great extent the capillarity of the wick, so that the oils and vapors are no longer transmitted. The compound which I preferably employ and have found to answer well in practice is composed of one-half pound of Portland cement, one-half pound asbestos, eight ounces of a practically-saturated aqueous solution of alum, and two ounces of a saturated aqueous solution of common salt. The cement and asbestos are 60 mixed together with the aqueous solutions and form a paste with which the portion a of the wick may be treated. Of course it is obvious that the proportions and perhaps some 70 of the ingredients may be changed without departing from the spirit of my invention.

I do not desire or intend to limit this invention to the particular substances described for rendering a portion of the wick incom- 80 bustible, as I am not aware that any one before my invention has ever produced a candle in which the wick has been so treated with a compound that the fire may travel through a portion thereof and be stopped at 85 another portion thereof before the candle has been fully burned by the hardened compound which practically destroys the capillarity of the wick.

Having fully described my invention, what 90 I claim as new, and desire to secure by Letters Patent, is—

1. A candle having a wick extended throughout the length thereof, the said wick at a portion between its ends being treated with a 95 compound of asbestos and cement which will harden when heated to thereby extinguish the flame.

2. A candle having a wick extended throughout the length thereof, a portion of said wick 100 near the base of the candle being treated with a compound which will harden when heated to thereby extinguish the flame.

In testimony whereof I have signed my name to this specification in the presence of 105 two subscribing witnesses.

THOMAS J. GARRIGAN.
